UNITED STATES PATENT OFFICE.

MARSHALL MERITT COPE, OF NOYO, CALIFORNIA.

SAW-HANDLE.

SPECIFICATION forming part of Letters Patent No. 498,626, dated May 30, 1893.

Application filed December 31, 1892. Serial No. 456,898. (No model.)

To all whom it may concern:

Be it known that I, MARSHALL MERITT COPE, a citizen of the United States, residing at Noyo, Mendocino county, State of California, have invented an Improvement in Saw-Handles; and I hereby declare the following to be a full, clear, and exact description of the same.

My invention relates to the class of saw-handles adapted to be readily fitted and adjusted to the saw and removed again when necessary.

My invention consists in a stock having a forwardly projecting flange provided with holding pins or lugs for engaging the holes in the saw blade, a sliding clamp fitted to the stock and adapted to bear on the rear edge of the saw and hold it tightly on the pins, and an oscillatory handle in rear end of the stock provided or formed with a cam acting against the sliding clamp to force it to its work and to relieve it, all of which, together with details of construction and arrangement I shall hereinafter fully describe.

The object of my invention is to provide a simple and effective saw-handle adapted to be readily fitted to the saw-blade, and as easily removed when necessary.

Referring to the accompanying drawings for a more complete explanation of my invention,—Figure 1 is a perspective view of my saw-handle, showing it applied. Fig. 2 is a longitudinal section of same.

A is the stock having a forwardly projecting flange a in which are the holding pins or lugs a' . Upon this flange is mounted and adapted to slide the clamp B, which is formed with an overhanging top lip b , and a rearwardly extending shank b' playing in a groove a^2 in the stock and having a cross-head b^2 by which it is confined. The rear end of the stock is formed with socket bearings a^3 in which is fitted and adapted to oscillate the sleeve C, which is formed or provided with a cam c adapted to impinge upon the cross-head b^2 of the clamp shank. This sleeve receives the handle D, or if preferred, it may form part of the handle itself.

The use of the device is as follows: The rear end of the saw S is provided with holes which fit over the pins or lugs a' , so that the

saw rests upon or against the flange a of the stock. The handle D is then turned, whereby the cam c bearing against the rear or inner end of clamp B, forces said clamp forwardly 55 against the edge of the saw, with the lip b of the clamp overlapping said edge. Thus the saw is bound and firmly held upon the pins or lugs.

To remove the device, the handle D is turned 60 in the opposite direction whereby its cam c relieves the clamp which, upon being pushed back, will permit the saw to be removed from the holding pins or lugs.

In order to fit the device to saws having 65 different holes, one of the holding pins or lugs a' may be made adjustable in the flange a of the stock. This may be done by having a slot a^4 in the flange, in which the lug may be moved and said lug may be set by a thumb 70 nut a^5 .

Having thus described my invention, what I claim as new, and desire to secure by Letters Patent, is—

1. A saw-handle consisting of a stock having 75 a forwardly projecting flange provided with holding pins or lugs over which the saw is fitted, a sliding clamp fitted to said stock and playing over its flange whereby it is adapted to be set up to and removed from the rear 80 edge of the saw, and an oscillatory handle or piece mounted in the rear end of the stock and having a cam adapted to bear upon and to relieve the rear end of the clamp, substantially as herein described. 85

2. A saw-handle consisting of a stock having 90 a forwardly projecting flange provided with holding pins or lugs over which the saw is fitted, a sliding clamp fitted to said stock and playing over its flange whereby it is adapted to be set up to and removed from the rear edge of the saw, said clamp having a forwardly projecting top lip adapted to overlap the saw, and an oscillatory handle or piece mounted in the rear end of the stock and having a cam 95 adapted to bear upon and to relieve the rear end of the clamp, substantially as herein described.

3. A saw-handle consisting of a stock having 100 a forwardly projecting flange, an adjustable holding pin or lug secured to said flange and adapted to receive the saw, a sliding clamp

fitted to said stock and playing over its flange whereby it is adapted to be set up to and removed from the rear edge of the saw, and an oscillatory handle or piece mounted in the 5 rear end of the stock and having a cam adapted to bear upon and to relieve the rear end of the clamp, substantially as herein described.

In witness whereof I have hereunto set my hand.

MARSHALL MERITT COPE.
